UNITED STATES PATENT OFFICE.

ISAAC H. HAAS, OF ATLANTA, GEORGIA.

BEDSTEAD.

1,260,536.

Specification of Letters Patent. Patented Mar. 26, 1918.

Application filed April 30, 1917. Serial No. 165,552.

To all whom it may concern:

Be it known that I, ISAAC H. HAAS, a citizen of the United States, residing at Atlanta, in the county of Fulton and State of Georgia, have invented certain new and useful Improvements in Bedsteads, of which the following is a specification.

The present invention relates to improvements in bedsteads and particularly to an improved lock or fitting for connecting the head and foot sections with the frame or mattress supporting parts.

The invention is particularly adapted for use with metal beds and in the accompanying drawing is shown as embodied in a three-piece bed.

The object of the invention is to provide a simple and inexpensive means which will produce a rigid connection between the frame and head and foot sections of the bed whereby the frame will be firmly supported and the several parts locked against accidental displacement.

In the accompanying drawing:

25 Figure 1 is a perspective view of a three-piece metal bed embodying the present invention.

30 Fig. 2 is a detail view in horizontal section, on an enlarged scale, through one of the posts or standards.

35 Fig. 3 is a sectional view on the line 3—3 of Fig. 2.

40 Fig. 4 is a similar view taken on the line 4—4 of Fig. 2.

45 Fig. 5 is a detail view showing the improved bracket and lock device in perspective.

50 Referring to the drawing, A, B respectively designate the head and foot sections of a bed, each comprising as usual suitable posts or standards C and intermediate connecting parts.

55 The frame of the bed includes end and side rails D, E of angle iron connected as hereinafter more particularly described and a wire mattress or mattress support F which as shown is connected to and extends between the end rails D. As shown the end rails are provided at both ends with downwardly bent portions f to the inner faces of the side members of which the side rails E are directly connected as by rivets e. The members F are further connected with the side rails by straps G so that the entire frame forms a single rigid structure that

may be bodily separated from the head and foot sections A, B.

Each post or standard C is provided with a fitting or bracket which is adapted to support the frame and so engage the members thereof that relative movement between the frame and head and foot sections is prevented except the frame be moved vertically as in assembling or disconnecting the several parts of the bed.

60 The specific form of fitting or bracket shown comprises two similarly shaped plates H, I which are connected together and to the post by rivet bolts or other fastening means and are so related that they provide a slot adapted to receive the inwardly extending member f' of the adjacent downward bent end portion f of an end rail, the depending member d of which rail extends through and is supported by a notch formed in the plate I. Each of the plates H, I comprises two members extending substantially at right angles to each other and between which the post or standard C is received. The inner plate H is in direct contact with the post while the plate I is of such relative size that the section thereof which is not directly secured to the post is spaced or separated sufficiently from the corresponding member of the plate H to provide the slot above mentioned into which the depending member f' and the downwardly extending member d of the end rail extend.

65 It will be seen that the fitting or lock 70 formed as above described not only provides a support for the frame but co-operates with the end and side rails to positively prevent relative horizontal movement in any direction between said frame and the head 75 and foot sections. The walls of the slot formed in the lock or fitting closely embrace the members d and f' to prevent separation, in the direction of the length of the side rails, of the several members of the bed and 80 the inner edge of the member f' contacting with the inner face of the plate I below the notch formed in the upper edge thereof, or the contact between the outer edge of the fitting and the portion f of the downwardly 85 bent end of the rail D prevent relative movement between the frame and head and foot sections in the direction of the length of the end rails. The bed frame may however be 90 readily disengaged from or engaged with 95

100

110

the head and foot sections by movement in a vertical direction.

It will be evident that instead of forming the bracket or fitting from two plates as shown, a single block, properly slotted may be employed.

Having thus described the invention what is claimed and desired to be secured by Letters Patent is:

- 10 1. In a bedstead, the combination of a head section, a foot section, end rails of angle iron having one member extending horizontally and the other extending vertically therefrom, side rails secured to the end rails, and bodily separable therewith from the head and foot sections, and a bracket attached to each post of the head and foot sections and provided with a slot receiving the vertical, depending member 15 of the body of an end rail, said rail having bent end portions coöperating with the brackets with which the rail is engaged to prevent movement of the rail in the direction of its length relative to said brackets.
- 20

2. The combination with a post or standard of a bedstead, of a bracket secured to the post including two members extending at an angle to each other with the post between them, said bracket providing a vertical slot extending to an outer edge and the 25 upper end thereof, and the bracket member that extends at an angle to said slot having a notch in its upper end in alinement with said slot for the purpose described.

3. The combination with a post or standard of a bedstead, of a bracket formed of two superposed plates of substantially right angle form in cross section, corresponding sections of said plates being held together and secured to the post, the other sections of 30 said plates being spaced to provide a vertical slot that opens through the top and one edge of the bracket, the section of the outer plate that is attached to the post having at its upper end a notch that opens into said 40 slot for the purpose described.

In testimony whereof I affix my signature.

ISAAC H. HAAS.
